UNITED STATES PATENT OFFICE

PERCIVAL S. TICE, OF CHICAGO, ILLINOIS

CARBURETOR

Application filed May 21, 1928. Serial No. 279,411.

The purpose of this invention is to provide an improved construction in a carburetor for an internal combustion engine adapted to be supplied with the fuel by limited pressure as by gravity from a relatively elevated source. It consists in the elements and features of construction shown and described as indicated in the claims.

In the drawings:

10 Figure 1 is a vertical section axial with respect to the air and fuel mixture conduit of a carburetor embodying this invention.

Figure 2 is a section at the line 2—2 on Figure 1.

15 Figure 3 is a view at the plane indicated by the line 3—3 on Figure 2, being a partial side elevation of the body of the carburetor with certain parts removed.

Figure 4 is a section at the line 4—4 on Figure 1.

Figure 5 is a view at the plane indicated by the line 5—5 on Figure 2, being a bottom end view of the body with the bottom cap plate removed.

25 Figure 6 is a detail view at the plane indicated by the line 6—6 on Figure 2, being a partial side elevation of the body with certain parts removed.

Figure 7 is a view at the plane indicated by the line 7—7 on Figure 3, being a partial side elevation of the body with certain parts removed.

Figure 8 is a detail section at the line 8—8 on Figure 3.

35 Figure 9 is a detail section at the line 9—9 on Figure 6.

Figure 10 is a detail section at the line 10—10 on Figure 6.

Figure 11 is a detail section at the line 40 11—11 on Figure 3.

Figure 12 is a view similar to Figure 1 showing a modified form.

Figure 13 is a section at 13—13 on Figure 12.

45 Figure 14 is a section at 14—14 on Figure 12.

Figure 15 is a lower end plan view of the body of the carburetor with the bottom cap removed, as at the plane indicated by the line 50 15—15 on Figure 12.

The structure shown in the drawings comprises a body member, A, having an air and fuel mixture conduit, 20, leading from the air inlet, 21, at which the air enters substantially horizontally with a 90° bend upwardly to the upper end of said body at which it is adapted for mounting at the engine intake for discharge into the intake manifold, a choke valve, 23, being provided at the entrance, and the throttle valve, 24, being mounted at the upper discharge end.

In the upwardly extending part of said conduit there is mounted a Venturi sleeve, 26, having formed integrally with it a nozzle member, 27, of special form hereinafter more particularly described.

The body member comprises also a fuel chamber, 30, extending adjacent the upwardly extending part of the air and fuel mixture conduit at the side opposite the air inlet and choke valve, said chamber extending down around and under the convex side of the 90° bend mentioned.

The body also has a horizontally projecting hollow boss, 32, for pipe connection with the fuel source, said boss extending across the fuel chamber, 30, at about the level of the center of the air inlet, that is, at the rear convex side of the 90° bend, said boss being extended downwardly, as seen at 32a, within the fuel chamber at the rear side of said bend, and terminating at about the level of the lower margin of the air inlet, where there is mounted in the downwardly protruding end of said boss, a valve fitting, 40, and valve therein hereinafter more particularly described.

A fuel chamber extending to the lower end of the body is closed at that end by a bottom cap, 45, conical in general form, with its conical cavity at the upper side, and having a marginal exteriorly protruding flange mated in dimensions with the lower end of the body for clamping between said lower end of the body and the bottom cap, a flexible diaphragm, 47, which thereby becomes effectively the capacity-limiting bottom of the fuel chamber, and above said diaphragm a damping plate, 48, which is a metal stamping flexed upwardly, as seen at 48a, at the central 95 100

area within the clamped margin, 48^b, and also folded at a diametrical line, as seen at 48^c, to present upwardly at opposite sides of said diametrical lines, downwardly sloping 5 areas, 48^d, converging at said line. This damping plate has a valved aperture, 48^e, near the depressed fold line for admitting liquid through it to the diaphragm, and vent apertures, 48^f, 48^g, near the clamped margin 10 at opposite sides to prevent trapping of air between the diaphragm and the damping plate.

The diaphragm, 47, has at its under side a sheet metal disk, 49, reinforcing the diaphragm at a relatively large central circular portion of its area, limiting the flexure of the diaphragm to the annular area, 47^b, outside said reinforced central area, and there is provided at the lower side of the diaphragm 20 a coil spring, 50, reacting between the metal disk, 49,—and thereby between the diaphragm, 47,—and an adjusting screw, 51, which is screwed into the lower end of the bottom cap, 45, said spring being centered 25 at its upper end upon the nut, 61, by which the disk, 49, is clamped to the diaphragm, the lower end of the spring being centered upon the reduced inner upper end, 51^a, of the tensioning screw 51.

30 The center pin, 62, having a wide flange, 63, for clamping the disk, 49, to the diaphragm by the nut, 61, as mentioned, extends upwardly through a central opening, 48^e, in the damping plate, 48, for encountering at 35 its upper end the free end of a lever, 64, fulcrumed at 65, on a bracket, 48^f, mounted on the damping plate near the margin thereof for operating a valve, 70, which is seated downwardly in the valve fitting, 40, above 40 mentioned. This valve fitting is screwed into the lower downwardly protruding end, 32^a, of the boss, 32, and has at its lower end an upwardly facing seat, 40^b, for the valve, 70, which seats downwardly, opening upwardly, 45 and thereby against the liquid inflow through the boss, 32. The fuel chamber, 30, has an atmosphere vent, 30^a, at its upper end.

From the foregoing construction it may be understood that the operation for fuel supply to the chamber, 30, is that when the chamber is empty, the reaction of the spring, 50, upon the flexible diaphragm, 48, operates for holding the valve, 70, at open position; and that as the fuel supplied by gravity or pressure enters through the duct in the boss, 32, it is discharged past the valve, 70, and through the apertures, 48^f, 48^g, in the damping plate, 48, accumulates above the diaphragm, 47, and continues to accumulate in 55 the chamber, 30, until the hydrostatic pressure of the liquid column thus accumulated operating upon the diaphragm, 47, is sufficient to overcome the resistance of the spring, 50, causing the diaphragm to be depressed 60 and allow the valve, 70, to descend to its seat

where it will be held seated by the pressure of the liquid column in the chamber, 30. The tension of the spring, 50, will be adjusted to limit the height to which the fuel will accumulate in the chamber, 30, before operating the diaphragm to allow the valve, 70, to be closed, to a level slightly below the discharge of the nozzle, 27, whose connection for such discharge will now be described.

The nozzle, 27, formed, as stated, integral- 75 ly with the Venturi sleeve, 26, is in the form of a bridge extending diametrically across the Venturi passage at the throat, said bridge having a longitudinal passage, 27^a, from which lead intermediate the ends, a plurality 80 of upwardly discharging ports, 27^b, having their upper ends opening at the bottom of a transverse notch, 27^c, in the upper side of the nozzle bridge, said bridge having also fuel passages, 27^d, 27^e, leading in from its 85 opposite ends and terminating in restricted discharge ports, 27^e, which open for discharge at the opposite ends of the notch 27^c, and thereby immediately above the level at which the ports, 27^b, discharge upwardly in 90 said notch.

For leading the fuel from the fuel chamber to the longitudinal passage, 27^a, of the nozzle bridge, the body, A, is formed at opposite sides of the air and fuel mixture conduit with circularly protruding bosses, 70 and 80, respectively, having circular recesses, 70^a and 80^a, respectively, which become variable capacity chambers by being closed or covered by flexible diaphragms, 71 and 81, respectively, which are clamped at their margins between the marginal areas of the bosses, 70 and 80, respectively, by cover members, 72 and 82, respectively, having their marginal flanges, 72^a and 82^a, mated with the marginal areas of the bosses for so clamping the diaphragms. Access for fuel from the fuel chamber, 30, to the variable capacity chambers, 70^a and 80^a, respectively, is afforded by ports, 74 and 84, respectively, controlled by check valves, 75 and 85, respectively, opening for flow from the fuel chamber into said variable capacity chambers and seating against reverse flow.

Substantially at the vertical plane of the 115 common axis of the two variable capacity chambers, there are formed in the body member, A, at opposite sides of the air and fuel mixture conduit and inwardly from the variable capacity chambers, respectively, vertically extending ducts, 76 and 86, respectively, which open at their upper ends by transverse ducts 77 and 87, respectively for registration with the opposite ends of the longitudinal passage, 27^a, of the nozzle bridge. Flow communication from the variable capacity chambers to the ducts, 76 and 86, respectively, is afforded by ports, 78 and 88, formed in the inner walls of said variable capacity chambers, respectively, and opening at their inner 120 125 130

ends in said ducts, 76 and 86, respectively. These ports are desirably provided with flow-restricting fittings, 79 and 89, respectively.

The purposes of these variable capacity chambers with their respective flexible diaphragm walls are to afford momentary or instantaneous increases of fuel supply under certain conditions of engine operation. For this purpose in respect to the variable capacity chamber, 70^a, the diaphragm, 71, has secured to it at the center a stem, 71^b, by which also there are clamped upon opposite sides of the diaphragm rigid disks, 71^d, limiting its flexure to an annular area outside said disks, and there is provided a spring, 71^c, reacting on the stem for flexing the diaphragm outwardly to give the chamber, 70, a maximum capacity. For housing the spring, 71^c, and guiding the diaphragm stem in its action, there is provided a sleeve, 71^a, for which the inner wall of the chamber, 70^a, is bored, the bore extending across the duct, 76, and the sleeve being inserted therein blockading the duct at that point.

The inner end of the diaphragm stem, 71^b, is dimensioned for slide fit in said sleeve, 71^a, is bored at its inner end for seating and centering the spring, 71^c, whose opposite end is centered in a slight central recess, 71^e, at the inner end of the bore which is occupied by the sleeve, 71^a. The chamber, 70^a, being thus normally expanded to maximum capacity, and being normally filled with the fuel from the fuel chamber, it will be understood that upon the diaphragm being thrust inwardly for reducing the capacity of the chamber, the fuel will be forcibly discharged from the chamber by way of the restricted port in the fitting, 79, thus momentarily and instantaneously increasing the fuel discharge, the check valve, 75, seating against flow from the variable capacity chamber back to the fuel chamber, ensuring that the chamber-reducing movement of the diaphragm will thus eject the fuel toward the nozzle and not drive it back into the fuel chamber. The diaphragm is operated for this fuel discharging movement by a lever, 90, fulcrumed at 91 on a bracket arm, 72^b, which projects from the closure member, 72, of the variable capacity chamber, 70, the lower terminal of said lever, 90^c, bearing against the protruding end of the diaphragm stem, 71^b, and the other end of the lever which extends upward and inwardly toward the throttle lever stem, terminates bearing against the hub of the throttle valve operating lever, 24^a, in position for encounter by a cam projection, 24^c, on said hub in the initial opening movement of the throttle valve, whereby, as may be understood from Figure 2, such initial opening movement operates the lever in the direction for thrusting the diaphragm, 71, inwardly, as described, for reducing the capacity of the chamber and ejecting the fuel therefrom.

The utility and importance of the feature of this part of the construction, viz., the bridge nozzle member, 27, consisting in that said bridge nozzle has a connection at opposite ends for fuel discharge, will be obvious upon considering that the variable capacity chambers by the movement of whose diaphragms, 71 and 81, respectively, the fuel is delivered under the conditions described to the nozzle, are necessarily arranged at opposite sides of the fuel mixture conduit which creates a problem for avoiding complicated and difficult construction, due to the extension of the discharge ducts from said chambers respectively at opposite sides of said conduit. This problem is solved in the construction shown by providing connection with the bridge nozzle at opposite ends of the latter.

In the case of both the variable capacity chambers, 70^a and 80^a, in order that they may fill completely with the liquid, avoiding trapping of air at the upper part, there are provided restricted vent ports, 70^m and 80^m, respectively, opening into the fuel chamber, 30. These vent ports are utilized for effecting a limited governing of the momentarily increased fuel discharge which is caused by the chamber-reducing movement of the diaphragm, rendering that discharge less forcible when the fuel is relatively hot,—as when the engine has been running and become heated, causing the carburetor to be somewhat heated,—so that it flows more freely under a given impulse than when the fuel is cold as at starting the engine after a long interval of rest. This governing function is obtained by providing temperature-responsive valve members which, as shown, are bi-metallic strips, 70ⁿ and 80ⁿ, secured at one end to the fixed wall of the variable capacity chamber, and having the free end lapping valve-wise on the vent port; the two metals of which the strip is composed being related as to rate of expansion by increase of temperature, so that when cold the valve end of the strip is seated at and closes the vent port; and when the temperature rises to a predetermined degree the flexure of the bi-metallic strip withdraws the valve end from the port correspondingly to the rise of temperature which the strip derives mainly from the fuel which occupies the chamber. The variable vent which is thus effected for the fuel, permitting its escape back into the fuel chamber under the impulse of the capacity-reducing movement of the diaphragm, causes variation inversely but to a corresponding degree of the amount of fuel which the impulse will discharge to the duct leading to the nozzle.

For the purpose stated in respect to the variable capacity chamber, 80^a, which serves a similar function by a different means, the construction comprises a spring, 81^c, reacting between the diaphragm, 81, and the diaphragm

clamping and cover member, 82, the spring being centered at its inner end by a boss, 81^b, at the center of the disk, 81^a, which bears upon the central area of the diaphragm, limiting its flexure to an annular area, 81^a, and at the other end by a boss, 82^a, projecting inwardly from the diaphragm clamping and cover member, 82. At the center of the chamber, 80^a, the inner wall of the chamber is bored 5 intersecting the duct, 86, and in the bore there is mounted a valve fitting, 83, which protrudes across the duct, 86, and has ports, 83^a, opening into the duct; and in this fitting there is mounted a valve, 84^a, having its stem protruding from the fitting for encounter of the diaphragm, 81, a spring, 85, being provided at the opposite end reacting against the inner end of the fitting, 83, for holding the valve normally seated outwardly with respect to the fitting, that is, toward the diaphragm, so that the intrust of the diaphragm under the stress of the spring, 81^c, opens the valve, so that the valve will be seated by the spring, 85, upon any action by which the diaphragm is moved against the action of said spring, 81^c, 20 for enlarging the chamber, 80^a.

For co-operating with the construction, as described, of this variable capacity chamber, 80, there is formed in the wall of the air and fuel mixture conduit, a duct, 101, which at its upper end opens through a small port, 101^a, inwardly beyond the seated position of the throttle valve, 24, and at the lower end this duct opens by a transverse duct, 101^b, through the diaphragm clamping margin of the chamber, 80^a, which duct registers with a duct, 101^c, in the diaphragm clamping and cover member, 82, said duct leading into the chamber, 82^c, of said diaphragm clamping and cover member at the opposite side of the diaphragm from the chamber, 80^a.

When the throttle valve, 24, is closed, the engine suction operating through the duct connection described, producing partial vacuum in the chamber, 82^c, causes the diaphragm to be retracted against the resistance of the spring 81^c, permitting the valve to be seated, so that the flow of fuel through the chamber, 50 80^a, to the duct, 86, is only that which takes place through the restricted fitting, 89, passing thence around the fitting, 83, for which passage said fitting is reduced in diameter at its inner end, as seen in Figure 2. Upon 55 opening the throttle, the resulting diminution of suction,—increase of pressure,—operating through the duct connection described to the chamber, 82^c, causes the diaphragm to be flexed inwardly, reducing the capacity of the chamber, 80^a, opening the valve, 84^a, and causing discharge of fuel past said valve and out through the ports, 83^a, in the valve fitting, 83, and by way of the duct, 86, to the nozzle, 60 thus instantaneously and momentarily in-

creasing the fuel discharge to the fuel mixture chamber.

For the purpose of affording limited supply of fuel during idling, that is, when the throttle valve, 24, is nearly closed, there is formed 70 in the wall of the air and fuel mixture conduit, a duct, 100, which at its upper end communicates by a passage, 100^a, with said conduit beyond the seating position of the throttle valve, and at its lower end by a cross passage, 100^b, with the nozzle bridge duct, 27^c, the communication with both ducts being effected by means of an annular groove, 27^c, in the outer surface of the nozzle fitting, said groove extending somewhat more than 180° around 80 the fitting, and thereby connecting the two radial ducts, 27^c, so that both of them derive communication with the passages, 100^b and 100^a, leading to a point of fuel discharge beyond the seating position of the throttle valve. 85 When the throttle valve is closed, the high suction resulting from the closing of the throttle valve operating through this passage, takes the fuel which is drawn to the upper discharge ends of the ports, 27^b, of the bridge nozzle member, drawing it in through the ports, 27^c, and thus delivering the fuel to the engine beyond the throttle.

When the throttle valve is opened after having been closed during idling, the fuel which has been drawn into the passage, 100, and standing therein, constitutes a fuel supply which is promptly responsive to the suction at the nozzle bridge, which is increased upon the opening of the throttle valve, so that that supply is instantaneously available for enriching the fuel mixture in the immediately following strokes of the engine when such enriched mixture is required for accelerating 100 the engine action.

For priming the carburetor upon starting with the passages leading to the nozzle presumably, or liable to be empty, the body, A, is bored, as seen at 65, and counterbored, 110 as seen at 65^c, through a boss, a^c, the counterbored traversing the fuel chamber, 30, and the bore intersecting the duct, 76, as seen in Figure 10; and a needle valve device, 120, if fitted in said counterbore, its tapered terminal 120^a, extending in the bore, said valve having a shoulder, 120^b, which is adapted to seat at the shoulder formed by the counterbore. This valve, as shown, is designed to be operated by a direct thrust and pull, not being screwed in, but being fitted so as to be snugly held at adjusted position by having its outer end split, as seen at 120^d, and normally spread for being tightly held in the bushing, 120^c, which is screwed into the boss, a^c, for affording tight slide bearing for said valve. For priming, the valve will be pulled outwardly, thus opening free communication 120 from the chamber, 30, to the duct, 77, inde- 130

pendent of the passage through the restricted fitting, 79.

In the form shown in Figures 12, 13, 14 and 15, the provision for momentary increase of fuel supply for acceleration upon opening the throttle after an idling period and increased opening, are omitted and the fuel nozzle is of the more usual form extending and discharging axially with respect to the air and fuel mixture conduit.

The parts which are identical with the corresponding parts of the earlier figures are identically indicated by reference characters. The fuel nozzle, 27^x, is mounted at an apertured boss, 27^m, protruding from the convex side of the 90° bend of the air conduit through whose aperture, 27ⁿ, the nozzle, 27^x, is in communication with the fuel chamber at the lower part thereof, and as shown, directly, above the damping plate, 48, and governing diaphragm, 47.

In both the forms shown, 32^x represents a strainer interposed in the fuel inlet connection antecedent to the valve which controls the fuel flow into the fuel chamber.

I claim:

1. A fuel feeding apparatus for an internal combustion engine comprising a casing having an air and fuel mixture conduit, and adapted for mounting on the engine with said conduit communicating with the engine intake manifold, said casing having a fuel chamber provided above the fuel-accommodating space thereof; with a vent directly to the atmosphere for admitting atmospheric pressure unaffected by the running of the engine; a fuel passage from the lower part of said fuel chamber terminating for discharge in said conduit at a point below the level of the atmosphere vent of the fuel chamber, said chamber having connection for receiving fuel by pressure from a fuel source, a valve for controlling fuel inflow to the chamber, said chamber having located bodily at the lower part a yielding wall member exposed to the hydrostatic pressure of the column of liquid which may be accumulated in the chamber, and operating connections from said wall member arranged to hold the valve closed when the fuel reaches a predetermined height in said chamber.

2. A carburetor for an internal combustion engine comprising a casing having an air and fuel mixture conduit and adapted for mounting on the engine with said conduit communicating with the engine intake manifold, said casing having a fuel chamber provided above the fuel-accommodating space therein with a vent directed to the atmosphere for admitting atmospheric pressure unaffected by the running of the engine; a fuel passage from the lower part of the fuel chamber, terminating for discharge in the fuel mixture conduit at a point below the level of the atmosphere vent of the fuel chamber, said

chamber having connection for receiving fuel by pressure from a fuel source, a valve controlling fuel inflow from said source, said chamber having a flexible diaphragm constituting part of its bottom wall and thereby exposed to the hydrostatic pressure of the column of fuel accumulated in the chamber, and operating connections from said diaphragm arranged to hold the valve closed when the fuel reaches a predetermined height in the chamber.

3. In the construction defined in claim 1, the valve being arranged for seating in the direction of fuel inflow to the fuel chamber, the wall member being resiliently maintained normally in position for holding the valve open against the inflow.

4. The construction defined in claim 1 having the air and fuel mixture passage extending generally in upward direction for connection with the engine intake manifold, the fuel chamber being located laterally with respect to said upwardly extending passage, and having its bottom formed by the yielding wall member.

5. The construction defined in claim 1 having the air and fuel mixture passage extending in generally upward direction for connection with the engine intake manifold, the fuel chamber being located laterally with respect to said upwardly extending passage and having its bottom formed by the yielding wall member, the connection for fuel inflow from the fuel source being lateral with respect to the fuel chamber at a point above the level of the yielding wall member, and by means of a passage leading downwardly within the chamber, and having the valve located at its lower end.

6. In the construction defined in claim 1, the fuel mixture passage extending in general upwardly for connection with the engine intake manifold, and at its lower end being flexed laterally for air intake transversely to said upward extent, the fuel chamber being located laterally with respect to the upwardly extending part and extending under the laterally flexed lower end, and having its bottom extending below said flexure, the yielding wall member being at the bottom and extending under the flexure, whereby without increasing the horizontal dimension of the entire device over all there is afforded for the yielding wall member at substantially horizontal position for exposure to the hydraulic pressure an area large relatively to the horizontal cross section of the chamber at the portion positioned laterally of said upwardly extending passage.

7. A fuel feeding apparatus for an internal combustion engine comprising a casing having an air and fuel mixture passage and adapted for mounting on the engine with said passage communicating with the engine intake manifold, said passage having a trans-

versely extending longitudinally apertured nozzle member, the casing having a fuel chamber extending in a vertical direction adjacent to said passage for containing fuel approximately to the level of the discharge of the nozzle member, said casing having ducts leading from the lower part of the fuel chamber and terminating in registration with the opposite ends of the longitudinal aperture of said nozzle member, the nozzle member having intermediate its ends upwardly discharging ports.

8. A fuel feeding apparatus for an internal combustion engine comprising a casing having an air and fuel mixture passage and adapted for mounting on the engine with said passage communicating with the engine intake manifold, said casing having a cavity constituting a fuel chamber positioned laterally with respect to and extending upwardly along said air and fuel mixture conduit, said fuel chamber being connected for receiving fuel from a source, and means for governing the level of the fuel in said fuel chamber, the casing having passages leading from the lower part of the fuel chamber at opposite sides of the air and fuel mixture passage to a level approximating the governed level of the fuel chamber, and a transversely extending longitudinally apertured nozzle member mounted in the fuel conduit having its opposite ends registering with said passages respectively and having intermediate its ends upwardly discharging ports.

9. A fuel feeding apparatus for an internal combustion engine comprising a casing having an air and fuel mixture passage and adapted for mounting on the engine with said passage communicating with the engine intake manifold, said casing having a fuel chamber extending up along one side of said air and fuel mixture passage and connected for receiving fuel from a fuel source, and means for governing the level of the fuel in said fuel chamber, fuel flow passages leading from the lower part of the fuel chamber at opposite sides of the air and fuel mixture passage and extending approximately to the governed level of the fuel chamber and opening for discharge of fuel in the air and fuel mixture conduit, said passages each comprising a variable capacity chamber, and means for momentarily reducing said chamber capacities for momentarily impelling therefrom the fuel therein through said fuel flow passages for discharge in the air and fuel mixture passage.

10. A fuel feeding apparatus for an internal combustion engine comprising a casing having an air and fuel mixture passage and adapted for mounting on the engine with said passage communicating with the engine intake manifold, a throttle valve controlling communication of said passage with the engine intake, said casing having a fuel chamber

open to atmospheric pressure above the fuel accommodating space thereof and connected for receiving fuel from a fuel source, and means for governing the level of the fuel in said fuel chamber, the casing having a fuel passage leading from the lower part of the fuel chamber terminating for discharge in the air and fuel mixture conduit approximately at the governed level of the fuel chamber, said passage comprising a variable capacity chamber having a diaphragm constituting one wall of the chamber flexible for enlarging and reducing the chamber capacity, a spring reacting on said diaphragm for flexing the diaphragm in the direction for enlarging the capacity chamber, and operating connections from the throttle for flexing the diaphragm in opposition to the spring in chamber-reducing direction in the initial opening movement of the throttle.

11. A fuel feeding apparatus for an internal combustion engine comprising a casing having an air and fuel mixture passage and adapted for mounting on the engine with said passage communicating with the engine intake manifold, a throttle valve mounted in said passage for controlling communication with the engine intake manifold, the casing having a fuel chamber extending vertically for containing fuel adjacent to the air and fuel mixture passage and having connection for receiving fuel from a fuel source, and means for governing the level of the fuel in said chamber, a fuel passage leading from the lower part of the fuel chamber and terminating for discharge of fuel in the air and fuel mixture conduit approximately at the governed level of the fuel chamber, said passage comprising a variable capacity chamber having a diaphragm constituting one wall of the chamber and flexible for enlarging and reducing the capacity of the chamber, and a spring reacting on the diaphragm for flexing it inwardly with respect to the variable capacity chamber, the casing having a duct leading from said variable capacity chamber and extending longitudinally of the air and fuel mixture conduit and opening therein beyond the seat of the throttle valve, whereby when the throttle valve is closed, suction of the engine operates for flexing the diaphragm in opposition to the spring in direction for enlarging the variable capacity chamber, and upon the opening of the throttle valve, the increase of pressure in the conduit beyond the throttle valve operates through said duct for flexing the diaphragm in the direction for reducing the variable capacity chamber for momentarily impelling the fuel therefrom in excess of the normal flow through the first mentioned fuel passage for discharge in the air and fuel mixture conduit.

12. In the construction defined in claim 11, the variable capacity chamber being com-

- prised in the fuel passage from the lower part of the fuel chamber to the point of discharge in the air and fuel mixture conduit by means of two ports of communication between said passage and said chamber, one of said ports having a check valve controlling communication through it opening for movement of fuel from the passage into the variable capacity chamber, the other port being restricted and otherwise uncontrolled.
13. In the construction defined in claim 11, the variable capacity chamber being constituted a part of the fuel passage by means of a port of communication between an antecedent portion of said passage and said chamber which is provided with a check valve opening for flow from said passage to said chamber, and a second port of communication between said passage and said chamber provided with a normally closed valve which is connected with the diaphragm wall of said chamber for movement to open it in the chamber-reducing movement of said diaphragm.
14. A fuel feeding apparatus for internal combustion engines comprising a casing having an air and fuel mixture passage and adapted for mounting on an engine with said passage communicating with the engine intake manifold, said casing having a fuel chamber extending along one side of the air and fuel mixture passage and connected for receiving fuel from a fuel source, the fuel flow passage leading from the lower part of the fuel chamber extending for discharge in the fuel mixture passage, said fuel flow passage comprising a variable capacity chamber, said chamber having a vent port at the upper part communicating with the fuel chamber, means for momentarily reducing said chamber capacity for momentarily impelling therefrom the fuel therein through the fuel flow passage for discharge in the air and fuel mixture passage, and a temperature responsive valve member mounted in the variable capacity chamber for controlling said vent port, arranged for seating the valve at the vent port at normal temperature as when the engine is cold, and for opening the valve as the temperature rises above a predetermined degree in excess of normal
